ATTORNEY
Walter Schlumpf

UNITED STATES PATENT OFFICE

WALTER SCHLUMPF, OF FANWOOD, NEW JERSEY, ASSIGNOR TO SHUR-CHEK COMPANY, INC., OF FANWOOD TOWNSHIP, NEW JERSEY

IDENTIFYING MECHANISM

Application filed August 4, 1932. Serial No. 627,426.

This invention relates to an improved identifying mechanism of the kind that employs a plurality of tags which are placed in racks and which is designed for receiving certain tags on certain racks and rejecting tags destined for other racks.

The apparatus is particularly adapted for use in laundries where they attach the tag to a bundle of laundry to be washed. This tag is the means for suspending the wash, usually placed in a bag or net, from the rack.

The object of the invention is to provide a rack which receives the tag easily, which prevents the entry of the wrong tags and which utilizes a simple flat tag.

Another object of the invention is to provide a rack which prevents the tags from sliding out of the rack without manual operation.

A still further object of the invention is to provide a rack which is constructed to allow the removal of a tag from the rack without passing it out through the end of the rack. This is of great advantage when a bundle is to be removed from a row of bundles suspended on the rack.

The invention is designed to be constructed with little cost as the parts are few in number and the construction is so simple that but few parts are necessary.

The invention is illustrated in the accompanying drawing in which Figure 1 is a side view of a rack and tags constructed in accordance with my invention. Figure 2 is a top view, partly in section, of the apparatus shown in Figure 1. Figure 3 is a section on line 3-3 in Figure 1. Figure 4 is a cross-section taken on line 4-4 in Figure 2. Figure 5 is a horizontal section of part of the track, the rocker and a tag showing the tag about to pass beyond the rocker. Figure 6 is a view similar to Figure 5 but showing the tag as it first engages the rocker. Figure 7 is a face view of the rocker. Figure 8 is a perspective view of a tag.

The device embodies a track with a longitudinal space between two rails. I show such track formed by two rails 10 and 11 being preferably made of a strip bent at one end into a return bend or loop 12. The track is

supported in arms 13 which fit into sockets 14 formed on the rail 10. This form of installation permits ready removal or installation of track. The arms 13 are suitably supported on the side wall 15 or other suitable support.

A tag 16 of generally flat shape slides edge-wise between the rails 10 and 11 and is suspended on at least one of the rails at the top edge. The form shown is crimped or curled at the top edge as shown at 17. The crimped or enlarged top end bears on the top of the rail 10 and the tag serves to suspend a bag or net of laundry. The bag is usually fastened by a safety pin 18 or its equivalent which is secured to the bottom of the tag. The drawing shows a ring 19 to which the pin 18 is fastened, the ring passing through a hole 20 in the lower part of the tag. The tag is easily placed on the track, the rails being placed as at 21 to make the entry easy and thus facilitate the work of sorting. It is usual to number a track or rack and number each tag for that track with the same numeral. To allow only the proper tags to go into the space in the track there is installed a check device in the form of a rocker 22.

The rocker is supported in a manner to place its two inner ends 23 and 24 in the space between the rails 10 and 11. The support shown comprises a band 25 forming a housing 28 for the rocker and extending over the tracks to be secured to the tracks 10 and 11 by the rivets or screws 26 and being raised at 27 to provide clearance for the enlarged tops 17 of the tags. The housing 28 supports a pivotal pin 29 on which the rocker is mounted and can freely rock to a limited extent. The track 11 is bent out as at 30 to form a space for the rocker.

The inner ends 23 and 24 of the rocker are adapted to co-operate with the faces of the tags to allow the proper tags to enter the track. The form illustrated shows two notches 31 in the end 23 of the rocker and one notch 32 in the end 24 of the rocker. The tags have projections or embossed parts to match the notches in the rocker. These embossed portions are separated longitudinally and laterally by distances equal to the longi-

tudinal and lateral distances between the notches. The tag shown has projections 33 to fit the notches 31 and a single projection 34 to fit the notch 32.

5 The rocker has the central recessed part 35 and the inclined or bevelled ends 36 and at the raised parts so provided I place the notches. The projections on the tag are inclined at the ends and these inclinations co-operate with the tapered ends of the rocker to move the rocker to a position where it will allow entry of a properly indentified tag.

This feature will be evident from Figures 2, 5 and 6. In Figure 6 a tag is just entering the track and engages the rocker by its projection 34, first engaging one of the faces 36 of the rocker. The engagement of the projection 34 with an inclined face 36 of the rocker swings the engaged end of the rocker 20 out of the way. This is shown in Figure 6. As the tag proceeds it moves the rocker to a balanced position due to the bevel projection engaging the other end 24. When the rocker is so positioned the projections 33 and 34 25 readily pass through the recesses 31 and 32. As the tag passes beyond the rocker it moves the rocker again to a blocking position as the projections 33 are out of line with the notch or recess 32 of the end 24. The proper tag 30 will therefore place the rocker in receiving position as it passes into engagement with the rocker and also place the rocker in blocking position as it leaves the rocker. It will be evident that very many various combinations of notches and recesses are available to insure against installation of the wrong tags.

The track 10 is depressed at 37 to form a stop shoulder 38. This prevents the removal or sliding back of tags without their being 40 lifted clear of the shoulder.

To enable a tag to be removed without moving it out through the stop or rocker, I provide an inclined channel 39 in the rail 10. This channel is large enough to receive the 45 enlarged part of the tag but is inclined at an angle so sharp that the tag will not ride down into it under normal use. In other words, the tag must be sharply tilted before it can be passed out.

50 Various changes may be made in the size and shape of the parts without departing from the scope of the invention.

I claim:—

55 1. A rack having a channel for receiving a tag, a rocker projecting into the channel and having notches in its ends, in combination with a tag having projections spaced to fit the notches of the rocker.

60 2. A rack having a channel for receiving a tag, a rocker projecting into the channel and having notches in its ends, in combination with a tag having embossed portions spaced longitudinally and laterally to simultaneously engage the notches in the rocker.

65 3. A rack comprising a pair of spaced rails,

a rocker secured with its two ends projecting into the space between the rails, a flat tag to fit into the space and having means to suspend it by the rails, the rocker having its ends provided with notches, and the tag having one face provided with projections spaced the same as the notches of the rocker. 70

4. An identifying mechanism comprising a track having parallel rails with a narrow space between them, a flat tag adapted to be slid edgewise into the space and having means for supporting the tag on at least one of the rails, a means at the entrance end of the slot for resisting the entrance of tag into the slot, and co-operative means on the tag 75 and the resisting means for moving said resisting means to allow the entrance of the tag. 80

5. An identifying mechanism comprising a track having parallel rails with a narrow space between them, a flat tag adapted to be slid edgewise into the space and having means for supporting the tag on at least one of the rails, a rocker at the entrance end of the track and having two ends adapted to alternately enter the space between the rails, 85 said ends having recesses therein, and projections on the tag to enter the recesses for passage of the tag and for engaging the said ends for moving the rocker into receptive position. 90

6. An identifying means comprising a pair of parallel rails close together to receive a tag edgewise between them, a tag to enter the space between the rails, one of the rails having a depressed part with a shoulder at the end toward the entrance end of the rails to prevent accidental outward passage of a tag on the rails, said tag having a shoulder at the top to rest on said rail having the depressed portion. 95

7. An identifying mechanism comprising a track having two rails spaced apart and adapted to hold tags placed edgewise in the track, a tag having a projection at the top to rest on one of the rails, said rail having an inclined outwardly offset portion to allow the withdrawal of a tag. 100

8. An identifying mechanism comprising a track consisting of two parallel rails to receive tags between them and to support said tag on the top of one rail, said rail having an inclined outwardly extending portion to permit the removal of the supporting part of a tag through said portion. 110

In testimony whereof he affixes his signature. 115

WALTER SCHLUMPF.
